Application filed April 7, 1910. Serial No. 554,081. Term of patent 14 years.

To all whom it may concern:

Be it known that I, HENRY D'OLIER, Jr., a citizen of the United States, residing at Philadelphia, State of Pennsylvania, have invented a new, original, and ornamental Design for a Shade or Reflector Holder, of which the following is a specification.

Reference is to be had to the accompanying drawing, in which:

The distinguishing characteristics of my design are the cylindrical portion 1 joined by fillet 2 with the base portion 3 having

the bead 4, the cylindrical portion 1 being surmounted by the part 5 of smaller diameter.

This shade or reflector holder is particularly ornamental in its use in supporting a shade or reflector upon an incandescent lamp socket or fixture.
